US0D1108639S

(12) **United States Design Patent** (10) **Patent No.:** **US D1,108,639 S**
(45) **Date of Patent:** **** Jan. 6, 2026**

(54) **PAIR OF HEARING AIDS**

(71) Applicant: **Tianmei Medical (Shenzhen) Co., Ltd.**, Shenzhen (CN)

(72) Inventor: **Min Lin**, Shenzhen (CN)

(73) Assignee: **Tianmei Medical (Shenzhen) Co., Ltd.**, Shenzhen (CN)

(**) Term: **15 Years**

(21) Appl. No.: **29/994,423**

(22) Filed: **Mar. 27, 2025**

(51) LOC (15) Cl. **24-99**

(52) U.S. Cl.

USPC **D24/174**

(58) **Field of Classification Search**

USPC D24/106, 173, 174; D29/112; D14/223

CPC A61F 11/08; A61F 11/085

See application file for complete search history.

Assistant Examiner — Kelly L Gross

(74) Attorney, Agent, or Firm — Allen James Oh

(57) **CLAIM**

The ornamental design for a pair of hearing aids, as shown and described.

DESCRIPTION

FIG. 1 is a front perspective view of a pair of hearing aids, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the pair of hearing aids, which form no part of the claimed design.

1 Claim, 8 Drawing Sheets
